ASH TRAY

Aloysius W. Becker, Chicago, Ill.

Application September 22, 1943, Serial No. 503,387

1 Claim. (Cl. 131—240)

This invention relates to improvements in ash trays and it consists of the matters hereinafter described and more particularly pointed out in the appended claim.

One of the objects of the present invention is to provide an ash tray which eliminates fire hazards from burning cigarettes placed thereon, so that the tray is safe in use.

Another object of the invention is to provide an ash tray which prevents the ashes therein from being blown therefrom by an ordinary draft, so that it assures cleanliness about its place of use.

A further object of the invention is to provide a tray of this kind which may be made from non-critical material and is of a simple construction which permits a positive cleaning thereof so as to remain sanitary and free from objectionable odors.

Also, it is an object of the invention to provide an ash tray which is so constructed that when a lighted cigarette is supported in part upon the rim of the tray and burns away, the remaining part of the cigarette will positively fall into and not outside of the tray to constitute a fire hazard.

Furthermore, it is an object of the invention to provide an ash tray that includes within the same, a support having cigarette receiving grooves so constructed that cigarettes placed therein will not become wet and soggy.

Again, it is an object of the invention to provide a tray of this kind that is so constructed as to include a snuffer whereby the lighted cigarette placed therein is almost instantly extinguished without damage, rising smoke or altered taste when relit.

The above mentioned objects of the invention, as well as others together with the advantages thereof will more fully appear as the specification proceeds.

In the drawing:

Fig. 1 is a top plan view of an ash tray embodying one form of the invention therein.

Fig. 2 is a vertical sectional view through the same as taken on the line 2—2 of Fig. 1.

Referring now in detail to that embodiment of the invention illustrated in the drawing, the improved ash tray includes a relatively shallow bowl-like body 5. The body, which in this instance is circular in plan, has a flat bottom wall 6 and an upstanding side wall indicated as a whole at 7. Rising from the central part of the bottom is a relatively low circular boss 8 that is concentric with the side wall.

The side wall is of a novel construction in that

it is of the greatest diameter at its mid portion or belt 9. The wall part 10 below said belt tapers inwardly and downwardly to join the periphery of the bottom wall while the wall part 11 above said belt tapers upwardly and inwardly to form a top edge 12 which is so narrow that a lighted cigarette may not easily be balanced thereon. A flange 13 tapers downwardly and inwardly from said edge to overhang a fairly considerable annular marginal portion of the bottom wall. The function of this flange will more fully appear later.

Associated with the bowl thus far described is an inverted cup-like member 14 that includes an upright annular side wall 15 and a top wall 16. The bottom end of the member has an inside diameter snugly but removably to fit about the periphery of the body boss 8 when the bottom edge of said side wall rests on the bottom 6 of the body.

The top surface of the top wall 16, which is herein shown as flat, is disposed in a plane slightly below that of the edge 12 when the member 14 is in place in the bowl body. In the top surface of the wall 16 of the member 14 is provided a plurality of V shaped grooves 17. As best shown in Fig. 1, there are four of such grooves arranged as a rectangle, with the ends of the grooves opening jointly through the periphery of the member. The grooves 17 are disposed tangentially to a circle having as its center a point in the vertical axis of the member 14 and each groove opens at both ends through the periphery of said member at the ends of at least two of the other of said grooves.

Also, in the top wall of the member 14 are provided openings 18 through which a cigarette may be inserted endwise for the purpose of snuffing out or extinguishing the same. Preferably said openings are of a diameter approximating the greatest width of the grooves 17 and one of said openings is disposed midway between the ends of each groove. When the member 14 is disposed in the bowl body 5 as shown in the drawing, an annular space 19 is formed between said member and the free edge of the flange 13 and which space opens into the interior of the bowl body.

The periphery of the member 14 is spaced one and five-eighth inches from the edge 12, as shown at the left hand side of Fig. 2. Therefore it has such a relation with respect to the edge 12 that when a conventional cigarette is supported partly on the top 16 of the member 14 and partly on said edge 12, that part of the cigarette project-

ing inwardly of said edge is much longer than that part of the cigarette projecting outwardly from said edge. This relation is apparent at the right hand side of Fig. 2 wherein a cigarette is shown in dotted lines at 20.

When the cigarette is lighted and it is desired to use the tray, one way is to engage the lighted end on the top 16 of the member 14, and to engage the other end upon the edge 12. A lighted cigarette will burn after it has been disposed as above mentioned. If it is not removed, it will burn away and when the burning end has cleared the periphery of the member 14, the cigarette will fall through the space 18 into the bowl, due to the overbalanced effect before noted. In this movement of the cigarette it first engages the flange 13 which directs it, end first, through the space 19 into the bowl.

Should the cigarette being smoked be placed in one of the holding grooves 17 as indicated in dotted lines 21 in Fig. 2, it is to be noted that a space is present between the bottom of the cigarette and the bottom of the groove. This space provides for the circulation of air therethrough so that the cigarette will not become wet and soggy at the lines of contact with the sides of the groove, due to condensation.

When the tray is in use, there is generally an accumulation of ashes and other matter in the bowl. Even though the tray herein is disposed in a draft, the moving ashes thereof are trapped by the overhanging flange 13 and prevented from blowing out through the space 18. Thus the surrounding surfaces remain clean and neat in appearance.

To extinguish a lighted cigarette, the lighted end thereof is inserted through an opening 18 until the lighted end engages the top surface of the boss 8. It will be thus extinguished almost instantly, allowing but a minimum escape of 40 smoke through the other holes 18.

The top surface of the member 14, while herein shown as smooth and flat, may include portions for holding packages or boxes of matches, or some emblem, ornament, or the like. The surface of the wall part 11, while herein shown as plain, provides an ideal space for decoration elements or for advertisements.

With the construction described, the danger of a lighted cigarette falling from the tray is eliminated and no matter how carelessly a lighted cigarette is placed on the tray, it will fall into the tray either when burned down or when the tray is jostled. Also, the flange 13 presents a good finger hold in picking up the tray from a flat surface.

In order that the size relationships may be better understood, some basic dimensions have been indicated of the form found advantageous for use with a conventional cigarette which has 20 a length of approximately 2 $\frac{1}{4}$ inches.

While in describing the invention I have referred in detail to the form and arrangement of the two parts constituting the tray, the same is to be considered only in the illustrative sense 25 so that I do not wish to be limited thereto except as may be specifically set forth in the appended claim.

I claim as my invention:

An ash tray embodying therein a body having 30 a bottom, a hollow inverted member removably seated on the bottom and having a top in which are V shaped cigarette holding grooves, said grooves being disposed tangentially to a circle having as its center a point in the vertical axis 35 of said member, with each groove opening at both ends through the periphery of said member at the ends of at least two of the other of said grooves.

ALOYSIUS W. BECKER.
